DESIGN FOR A MOUNTING FOR A HAND TELEPHONE

George R. Lum, New York, N. Y., assignor to Bell
Telephone Laboratories, Incorporated, New
York, N. Y., a corporation of New York

Application January 17, 1935, Serial No. 54,895

Term of patent 14 years

To all whom it may concern:

Be it known that I, George R. Lum, a citizen of the United States, residing at New York, in the county of New York and State of New York, have invented a new, original, and ornamental Design for a Mounting for a Hand Telephone, of which the following is a specification, reference being had to the accompanying drawing, forming a part thereof.

Fig. 1 of the drawing is a front elevational view of a mounting for a hand telephone, showing my new design;

Fig. 2 is a side elevational view;

Fig. 3 is a top plan view; and

Fig. 4 is a view in perspective thereof.

The mounting shown in the drawing is adapted to be mounted on a wall or on the side of a desk and to enclose switching means with which the hook is adapted to cooperate. The hook provides a support for a hand telephone, that is, a device having a telephone receiver and a telephone transmitter at the ends of a common handle or support.

I claim:

The ornamental design for a mounting for a hand telephone, as shown and described.

GEORGE R. LUM.
